LABORATORY STEAM HEATER FOR FLASKS OR THE LIKE

John M. Liptay, Manhasset, N.Y., assignor to Laboratory Furniture Company, Inc., Mineola, N.Y., a corporation of New York

Filed Jan. 9, 1961, Ser. No. 63,488

Term of patent 14 years

(Cl. D16—2)

FIG. 1

FIG. 2

FIG. 3

FIG. 4

FIG. 1 is a top perspective view taken from the front and right side of a laboratory steam heater for flasks or the like embodying my new design,

FIG. 2 is a front elevational view thereof on an enlarged scale,

FIG. 3 is a top plan view thereof on an enlarged scale, and

FIG. 4 is a bottom plan view thereof on an enlarged scale.

The dominant features of my design reside in the portions shown in solid lines.

I claim:

The ornamental design for a laboratory steam heater for flasks or the like, substantially as shown and described.
